UNITED STATES PATENT OFFICE.

JEFFERSON PATTEN, OF GREEN POINT, NEW YORK, ASSIGNOR OF PART TO CHARLES KENNEDY HAMILTON, JR., OF SUMMIT, IVERS A. GARD, OF BERGEN POINT, AND CHARLES H. MUNDY, OF METUCHEN, NEW JERSEY.

HYDROCARBON-BURNER.

SPECIFICATION forming part of Letters Patent No. 397,749, dated February 12, 1889.

Application filed March 23, 1888. Serial No. 268,285. (No model.)

To all whom it may concern:

Be it known that I, JEFFERSON PATTEN, a citizen of the United States, residing at Green Point, in the county of Kings and State of New York, have invented certain new and useful Improvements in Hydrocarbon-Burners, of which the following is a specification.

The object of my invention is to provide a burner for the economical and effective combustion of petroleum and other hydrocarbons, and adapted for application to a suitable stove or fire-place of any suitable form or construction.

My improved burner is constructed with a retort or vaporizing-chamber, into which the hydrocarbon is introduced through a pipe controlled by a suitable valve, a steam-generating chamber filled with asbestos or other capillary material to which water is supplied, a superheating-chamber to which the steam is conducted from the generating-chamber, and pipes leading from the vaporizing retort or chamber and the superheating steam-chamber and conducting the hydrocarbon vapor and superheated steam to a mixing pipe or nozzle, above which the vapors are burned, as hereinafter described.

In the accompanying drawings, Figure I is a vertical longitudinal section of my improved hydrocarbon-burner. Fig. II is a plan view of the pan containing asbestos to receive hydrocarbon for initial heating. Fig. III is a top view. Fig. IV is a plan view of chamber 1. Fig. V is a horizontal section on the line 5 5, Fig. I. Fig. VI is an elevation.

1 represents a flat horizontal chamber or retort, to which petroleum or other hydrocarbon is admitted through a pipe, 2, under control of a valve, 3. In the upper part of the retort 40 are any suitable number of radial ports or passages, 4, two of such passages being shown in the present illustration, which deliver the hydrocarbon vapors to conducting-pipes 5, from which horizontal pipes 6 conduct said 45 vapors to a mixing chamber or nozzle, 7, in the axis of the burner.

8 represents an annular generating-chamber filled with asbestos or other suitable capillary material, and provided with a screw-

cap, 9, by which said capillary material is compressed to any necessary extent to regulate the passage through it of water, which is introduced to said vaporizing-chamber through one or more pipes, 10, which may be connected with an ordinary domestic water-service. 50 When the burner is in operation, steam generated in the chamber 8 is conveyed by one or more pipes, 11, to a superheating-dome, 12, from which the steam, in a superheated or it may be decomposed state, is conducted by one 55 or more pipes, 13, to the nozzle 14 in the center of the mixing-chamber 7.

Above the chamber 7 is a deflecting-bonnet, 15, of frusto-conical form, having an opening in its apex located at or near the center of the 60 annular vaporizing-chamber, 8. In the lower part of the burner is a pan, 16, having a layer of asbestos, 16^a, in the bottom to receive a small quantity of oil through a nozzle, 17, under control of a stop-cock, 18, for the initial 65 heating of the burner.

The water-supply pipe or pipes 10 are made tight in the bottom of the pan 16 by a suitable packing, jam-nuts, or other proper means.

The operation is as follows: Petroleum or 70 other hydrocarbon being admitted to the retort or vaporizing-chamber 1 in suitable quantity through the pipe 2 and a suitable supply of water to the generating-chamber 8, a small quantity of oil is admitted to the pan 16 and 75 ignited to produce the initial heat, causing sufficient evolution of hydrocarbon vapor through the pipe 6 6 and chamber 7 to produce a flame above the deflector 15 and quickly to generate steam in the chamber 8, which 80 steam, passing up the pipes 11, is superheated in the dome 12, and thence descends with considerable force and pressure through the pipe 13 and jet-nozzle 14, mingling with the hydrocarbon vapor, which, when the apparatus is in 85 full operation, flows in efficient volume through the pipes 5 6 to the mixing-chamber 7. The mixed hydrocarbon and oxyhydrogen gases passing through the chamber 7 and deflector 90 15 are burned with intense heat over the whole 95 interior of the annular chamber 8 and above the same, imparting the necessary temperature to the entire apparatus, which thus con-

stitutes a highly effective burner for hydro-carbon oils.

The apparatus is complete in itself, needing only the addition of oil or water supplies. It 5 is extremely compact and convenient and well adapted for use in an ordinary heating-stove or in a fire-grate in connection with artificial logs or other accessories.

Having thus described my invention, the 10 following is what I claim as new therein and desire to secure by Letters Patent:

1. The combination, with the burner, the annular generator 8, the hydrocarbon-vaporizer 1, and steam-dome 12, of a pipe connecting said dome and generator and pipes connecting said dome and hydrocarbon-vaporizer with the burner, substantially as set forth.

2. In a hydrocarbon-burner, the combination, with the mixing-chamber or nozzle 7 and 20 the vaporizing-chamber 1, and the steam-generating chamber 8, arranged above said chamber 7, of the pan 16, for containing oil, arranged below said generating-chamber 8, and a superheating - chamber arranged above the

burner, connected with the chamber or nozzle 25 7 and also with the chamber 8, and said chamber or nozzle 7 being also connected with the vaporizing-chamber, as set forth.

3. In a hydrocarbon-burner, the combination, with the vaporizing - chamber and the 30 mixing-chamber 7, connected therewith, of an annular steam-generating chamber arranged around said chamber 7 and connected therewith, a porous filling in said annular chamber, and a screw-cap, 9, for compressing said 35 filling, substantially as set forth.

4. In a hydrocarbon-burner, the combination, with the steam-generating chamber and the mixing-chamber connected therewith, of the vaporizing-chamber, the radial passages 40 4, leading from said vaporizing-chamber, and pipes connecting said passages with said mixing-chamber, substantially as set forth.

JEFFERSON PATTEN.
